COMPOSITE DOOR

Fred A. Johnson, Chicago, Ill., assignor to Fred A. Johnson, Junior, Chicago, Ill.

Application September 11, 1937, Serial No. 163,364

1 Claim. (Cl. 20—35)

The present invention relates to composite doors, and is an improvement of my prior Patent No. 2,040,259, issued May 12, 1936.

One of the objects of the invention is the provision of an improved door construction by means of which the door may be made lighter and practically as strong as a solid door of the same size, with the use of less lumber.

Another object is the provision of an improved door construction by means of which doors may be constructed of relatively short and thin pieces of lumber, sometimes called "lath lumber" in the trade.

Another object is the provision of an improved door construction which may be manufactured more cheaply than the devices of the prior art and more cheaply than the specific construction in my prior patent, referred to, so that the door may be sold at a lower price and placed within the means of a larger number of purchasers.

Another object of the invention is the provision of an improved door construction which requires less mill work and which may be assembled more quickly and easily than the doors of the prior art, and which has a high degree of strength and rigidity and a very light weight.

Other objects and advantages of the invention will be apparent from the following description and the accompanying drawings, in which similar characters of reference indicate similar parts throughout the several views.

Referring to the drawings, of which there are two sheets,

Fig. 1 is an elevational view of a door constructed according to the present invention, with certain layers of the door broken away to show the internal construction;

Fig. 2 is a fragmentary sectional view, taken on the plane of the line 2—2 of Fig. 1, looking in the direction of the arrows;

Fig. 3 is a fragmentary vertical sectional view, taken on the plane of the line 3—3 of Fig. 1, looking in the direction of the arrows;

Fig. 4 is a fragmentary elevational view of the upper left corner of the door, with certain of the layers broken away, showing the details of construction of a door embodying my invention.

Referring to Fig. 1, 10 indicates in its entirety the composite door, which is preferably provided with a framework which comprises the vertical rails 11 and 12 and the horizontal rails 13, 14. The vertical rails comprise pieces of lumber which are substantially rectangular in cross section, as shown in Fig. 4, being provided with four plane

points on the inner side 17 with the rectangular slots 19.

The opposite rail 12 is likewise provided with opposed rectangular slots 20 located at the same level as the slots 19 in the rail 11. The upper and lower frame members 13, 14 have their main bodies of substantially rectangular cross section, but these rails are provided with the upwardly and downwardly extending ribs 21, 22; that is to say, the frame members 13 and 14 are morticed 10 on their inner surfaces.

The thickness of the rib 22 or 21 corresponds to the width of a plurality of cross frame members 23 which fit into the slots 19, 20 and are located at regularly spaced points in the door frame from 15 top to bottom.

Referring to Fig. 1, it will be noticed that the cross frame members 23 are approximately six inches apart; but, of course, this dimension may be varied considerably, and the amount of cross members used depends upon the strength of the door desired and the permissible weight for the door. Any suitable number of cross frame members 23 may be used, or any suitable spacing of them may be employed.

The upper and lower rails 13 and 14 are likewise provided with the flat sides 24, 25 and the flat upper edge 26. The flat end 27 of the upper rail 13 abuts against the flat face 17 of the vertical rail 11, to which it is secured by gluing, by means of a dowel pin 28 secured in suitable complementary cylindrical bores 29, 30 in the members 11 and 13. A similar mode of securing 20 is used at all of the four corners of the door between the members 11, 12, 13 and 14.

It should also be understood that all of the parts employed in the door are secured together by suitable gluing operations, without the necessity for utilizing any nails or securing devices other than those shown. Thus the cross frame members 23 are also glued in the slots 19 and 20.

The cross frame members 23 and the ribs 22 are covered by a multiplicity of vertically extending pieces of lumber 31, 33, etc., which may be several inches in width and of rectangular cross 45 section, and of such thickness that when the strips 31—33, etc. are applied to the sides of the ribs 22 and cross frame members 23, the outer faces of these strips lie flush with the door frame members 11—14. These vertical strips may consist of strips which extend the full length of the door, or they may consist of short pieces of lumber, known as "lath lumber", in which case the joints are always broken between adjacent strips, and the small and short pieces may be in-

terspersed with longer strips, some of which may extend the full length of the door to strengthen the frame.

These strips also are secured in place by gluing 5 the faces which oppose the edge of the cross frame members 23 to these members and by gluing the strips 31—33 edge to edge, and with their edges to the adjacent rails 11—14. The frame members 11 and 12 are then finished at their 10 edges or faces 15 with strips of finishing lumber 34, which are substantially rectangular in cross-section, and preferably thinner in the dimension which extends parallel to the plane of the door.

15 These strips 34—35 may be of more expensive wood, since they cover that portion of the door which is visible at the edges thereof, and in the same way the top and bottom of the door may be provided with additional strips, but that 20 is not necessary, as those edges are not usually accessible to the sight.

At the middle of the door, adjacent the point where the lock 36 is to be morticed in, the door frame is preferably provided with an additional 25 block 37, which may be as wide as one of the strips 31, and which substantially fills the space between the two adjacent cross frame members 23 at that point. Thus the part of the door where the lock is installed will be solid and will have 30 ample material for securement of the lock and the plates.

The two faces of the door frame thus constructed are then preferably covered with one or more layers of veneer 38, 39, 40 and 41, and preferably in all cases more than one layer is employed, the layers having their grain extending transversely to each other.

This veneer may be of more expensive wood also, so that the door may present the appearance 40 of a solid oak or solid mahogany door, if desired, or any of the known woods may be employed to cover the door frame, which is of the cheaper material. The veneer layers 39—41 are also glued to the frame so far described and to 45 each other and they extend to the extreme edge of the frame, covering the complete lateral faces of the door.

It will thus be observed that I have invented 50 an improved door construction which requires less parts than any of the devices of the prior art, but in which the door is light, yet stiff and strong. The edge-to-edge construction and securement of the strips 31—33, etc. between the edges of

the rails 11 and 12, and end rails 13 and 14, provides the door with all of the bracing which it requires.

The transverse strip 23, which are secured in slots, and which have their edges secured to the strips 31—33, etc. also serve to brace the doors so that there is no possibility whatever of the door sagging out of square, and all of the foregoing is additionally held in place by the layers 10 of veneer.

The present door is more economical to manufacture than that shown in my prior patent and may be produced at a lower cost. The present door is believed to be just as strong as the door of my prior patent, and much stronger than any 15 of the other prior art devices. It is lighter than any of the devices of the prior art, and by virtue of the low cost of the frame and lesser amount of lumber employed, it is a door which can compete in price with any of the devices of the 20 prior art.

While I have illustrated a preferred embodiment of my invention, many modifications may be made without departing from the spirit of the invention, and I do not wish to be limited 25 to the precise details of construction set forth, but desire to avail myself of all changes within the scope of the appended claim.

Having thus described my invention, what I claim as new and desire to secure by Letters 30 Patent of the United States, is:

A composite door comprising a pair of vertical frame members and a pair of horizontal end frame members secured together to form a substantially rectangular frame, with a multiplicity 35 of horizontal frame members extending from one vertical frame member to the other, said vertical frame members being provided with slots fitting the ends of said horizontal frame members, and a plurality of vertical frame members comprising slats glued to said latter horizontal frame members and glued together edge to edge, covering both sides of said frame from one vertical frame member to the other, and from one horizontal end frame member to the other, all of said 40 vertical slats being provided with grooves for receiving said latter horizontal frame members, and all of said parts being glued together, and a covering of ornamental material glued to said slats and rectangular frame-work, to provide a finished surface for the door.

FRED A. JOHNSON.
